United States Patent

Des. 236,138
Patented July 29, 1975

236,138

STATUE

Noel H. Smith, 204 Shamrock, Anniston, Ala. 36201

Filed Nov. 8, 1973, Ser. No. 413,763

Term of patent 14 years

Int. Cl. D11—02

U.S. Cl. D29—23 A

FIG. 4FIG. 3

FIG. 1 is a front elevational view of a statue showing my new design, the rear being plain and unornamented; FIG. 2 is a left side elevational view; FIG. 3 is a right side elevational view; and FIG. 4 is a top plan view.
I claim:

The ornamental design for a statue, as shown.
